UNITED STATES PATENT OFFICE

138,131

DESIGN FOR A HOLDER FOR RATION BOOKS AND TOKENS OR THE LIKE

Kenneth Aranoff, Lawrence L. Lavant, and Lester W. Arkin, Chicago, Ill.

Application March 15, 1944, Serial No. 112,914

Term of patent 3½ years

(Cl. D87—3)

To all whom it may concern:

Be it known that we, Kenneth Aranoff, Lawrence L. Lavant, and Lester W. Arkin, citizens of the United States, residing at Chicago, in the county of Cook and State of Illinois, have invented a new, original, and ornamental Design for a Holder for Ration Books and Tokens or the like, of which the following is a specification, reference being had to the accompanying drawing, forming part thereof.

Fig. 1 is a perspective view of a holder for ration books and tokens or the like showing my new design in open position;

Fig. 2 is an edge elevational view thereof in closed position; and

Fig. 3 is a cross-sectional view thereof on line 3—3 of Fig. 2 looking in the direction of the arrows.

The external cover portions, not shown, are substantially plain.

We claim:

The ornamental design for a holder for ration books and tokens or the like, as shown and described.
